STABILIZING INSERT FOR SHOES

John M. Hiss, Los Angeles, Calif.

Application December 3, 1945, Serial No. 632,374

1 Claim. (Cl. 36—71)

1

This invention relates to a stabilizing pad to be inserted or built into a shoe to aid the functioning of the human foot as it maintains body balance while standing and distributes the moving load during walking.

In the past, countless different types and kinds of devices have been provided for raising or lowering certain portions of the foot, for supporting arches and the like. Although these devices have differed from one another to some extent in their exact configuration and in the area supported, they are almost without exception directed to the general idea of supporting some portion of the foot in an attempt to maintain it in the position which nature intended. In this respect these prior art devices function very much like crutches in that they make the user less conscious of the condition but they do not correct it. As a matter of fact comprehensive functional checks indicate that supports of this type actually interfere with the natural foot function, and to a substantial extent, cause muscle atrophy.

It has long been recognized that certain types of foot ailments which affect over fifty percent of all feet, such as bunion joints, hammer toes, and foot eversion require the use of shoes which are particularly wide in the forepart in order that adequate room be provided to permit the proper fitting for the correction of this type of ailment. In constructing a shoe which provides sufficient room in the forepart it has been exceedingly difficult to obtain snug fitting in the backpart with the result that shoes of this type do not provide any means whatsoever for guiding the action of the heel and arch bones during walking. Consequently, the heel rolls medialward toward the midline of the body resulting in a displacement of the center of gravity toward the medial side of the foot and a shifting of the moving load away from its normal position on the lateral border of the foot. This causes muscle strain and great physical discomfort in many cases, all because the shoe is not balanced and the heel is not stabilized.

The foot is normally divided longitudinally into the lateral weight bearing portion or arch and the medial spring portion or arch. As previously stated, most of the weight is properly focused and balanced on the lateral side. In normal walking the weight bearing starts at the central portion of the heel, moves forward mostly to the lateral side of the foot and becomes focused at the balancing point and location of the cuboid bone which is on the lateral or outer side of the foot about midway between the central portion

2

of the heel and the metatarsal heads. As walking progresses the weight travels forward along the lateral side of the foot to the forepart where it moves medially or inwardly of the foot and across the metatarsal heads in an even distribution. Thereafter, the weight moves off the ends of the toes as the body is thrust forward. This normal distribution of weight in walking has been diagrammatically illustrated in Figure 8 of the drawings forming a part of this application, the arrows indicating the progress of the distribution of the weight and the heavier lines indicating the relative concentration.

Having due regard for the general concepts as herein described, the primary purpose of this invention is to provide a stabilizing means which aids in promoting proper weight distribution by maintaining the center of weight bearing in its proper balanced position at the cuboid bone and returning it to its normal position in the event of displacement.

Another important object of the invention is to provide in a foot stabilizing pad a cupped heel seat which stabilizes or anchors the heel bone by filling in the excess space in the extreme back part of the shoe.

Another object of the invention is to provide a stabilizing foundation pad which is elevated at the medial and forward portions of the heel in order to throw the weight to the lateral side of the foot at the beginning of the step.

Another object is to provide a stabilizing pad which includes a relatively firm and balanced base directly beneath the cuboid bone for supporting the foot and maintaining the equilibrium of the body when the weight is normally distributed as hereinbefore described.

Another object is to provide in a stabilizing pad a smooth, convex, and soft contour in the forepart to aid in the distribution of the moving weight load across the metatarsal heads at the end of the step. This prevents a localization of the weight at any one particular metatarsal head, which localization usually results in a painful callus formation.

Another object of the invention is to provide a stabilizing pad which is so constructed as to deliberately avoid supporting the medial spring arch by providing an unusually soft and flexible cushion in the area where this arch is located. In the preferred form of the invention this cushion may be made especially soft by vacuum cups or similar cavities and by hollowing out the underside of the pad. The provision of this soft cushion in the area of the medial spring arch

permits the shoe to be pulled up on the medial side as by lacing and the resilient pad thereby fills in some of the waste space and exerts a massaging effect on the muscles and blood vessels on the under side of the foot during walking.

Another object is to provide a stabilizing foundation pad of unitary construction in which various degrees of softness and firmness may be provided by using materials of different densities or by different types of material in combination.

Other and further objects and advantages will be apparent from the further and more detailed description when considered in conjunction with the accompanying drawing forming a part of this specification in which:

Figure 1 is a top view of a stabilizing pad representing a preferred form of the invention.

Figure 2 is a sectional view along the line 2—2, Figure 1, illustrating particularly the contours of the pad on the medial side of the foot.

Figure 3 is a sectional view along the line 3—3, Figure 1, similarly illustrating the contours on the lateral side of the foot.

Figures 4 and 5 are sectional views along the lines 4—4 and 5—5, Figure 1, respectively, and illustrate the contours of the cupped heel seat.

Figures 6 and 7 are sectional views along the lines 6—6 and 7—7, Figure 1, illustrating the contours and construction of the upper side of the pad toward the forepart thereof.

Figure 8 is, as previously stated, a diagrammatic view illustrating the normal transposition of weight from one portion of the foot to another during walking.

Figure 9 is a bottom plan view of a modified form of the construction in which the desired results are obtained and to some extent accentuated by securing elevator pads to the under side of an insert of the general type illustrated in Figure 1. These pads may be utilized particularly to avoid the necessity of providing inserts of different thicknesses.

Figure 10 is an elevational view of the modified form of the construction shown in Figure 9.

Figure 11 is a sectional view of another modified form of construction similar to Figure 2, the modified form having the same plan view as the form illustrated in Figure 1 but having different contours in elevation.

Figure 12 is a sectional view similar to Figure 3 of the modified form of construction shown in Figure 11.

Referring again to the drawings for a further and more detailed description of the invention, the stabilizing pad shown as an insert adapted to be inserted in or built into a shoe is indicated generally at 10, Figure 1. The pad is preferably formed from rubber having different densities over different portions of the area. However, other resilient materials may be used for the construction of the entire pad and it may be provided by combinations of various materials.

The heel cups which forms an important feature of the invention is constituted by the flange 11 which is extended upwardly around the periphery of the rear portion of the pad in general arcuate configuration and the depressed area 12 in which the heel bone is adapted to rest. The flange also extends forwardly on the medial side of the foot for a slight distance and a markedly raised area 13 is provided also on this side just rearwardly of the area of the spring arch. The purpose of the flange extension and the raised area 13 is to throw the weight laterally toward the firm portion of the pad 14 which rests directly be-

neath the cuboid bone. This portion, which has been shaded in Figure 1, is preferably of relatively hard and firm construction and rests flatly on the bottom of the shoe in order to provide

5 a strong and sure support for the cuboid bone during normal walking. This firm portion 14 is a very important element of this invention, as most shoes are decidedly unstable under their lateral portions. This relatively hard and firm portion strengthens the weak portion of an ordinary shoe and affords a balanced foundation for the cuboid bone, which in itself is the balancing point of the foot.

In the area adjacent the medial spring arch, 15 vacuum cups 15 or similar cavities may be formed on the upper side of the pad while the lower side 16 is preferably hollowed out. This portion of the pad is preferably formed of soft and flexible material for the purpose, as previously stated, of deliberately avoiding support of the arch at this point and providing a massaging effect on the muscles and blood vessels of the foot during walking.

Two rows of similar cavities or vacuum cups 17, 25 extending across the insert adjacent to the ends of the firm portion of the pad 14, give flexibility to allow the stabilizer to conform to the inner contours of a shoe and cooperate with the firm portion of the pad 14 permitting it to rest flatly 30 on the bottom of the shoe while allowing the soft and flexible portion of the pad to flex to give a massaging effect.

The forepart of the pad 18 in the area of the metatarsal heads is preferably arched slightly, as 35 shown in Figures 2 and 3, and is formed from material which is particularly soft and smooth, the purpose being to aid in the distribution of weight across the various metatarsal heads.

The operation of the pad in use as an insert 40 in or a component part of a shoe is diagrammatically illustrated in Figure 8 in which 19 indicates the heel area, 20 the area of the cuboid bone and 21 the area of the metatarsal head on a foot 22 of normal contours. The distribution of 45 weight through these various areas has been heretofore described.

In the modified form of the invention shown in Figures 9 and 10 elevator pads are shown secured to the under side of the stabilizer pad 10. These pads need not necessarily be of the exact configuration shown and may be cut by hand or stamped from rubber sheets distributed in conjunction with the stabilizer pads. The pad 23 is preferably positioned toward the front part of the heel area and rearwardly of the medial spring arch and is for the purpose of throwing the weight toward the lateral side of the foot in the area of the pad 24 positioned directly beneath the cuboid bone. This pad is preferably skived on the side toward the center of the foot. The pad 25 is positioned directly beneath the metatarsal heads. Pads 24 and 25 may both have bevelled or skived edges as shown to lessen their protuberance. The importance of these pads arises from the fact that, in order to accommodate the stabilizer pad to various types and sizes of shoes, it is necessary to provide it in various different thicknesses. This can be avoided and a comparable result obtained by affixing to a stabilizer pad of relatively thin construction, the elevator pads 23, 24 and 25 in order to build it up to the equivalent of a stabilizing pad of thicker construction. The pads may be secured in position by adhesive or in other appropriate ways.

75 In the modified form of the invention shown

in Figures 11 and 12, the insert, although having the plan view shown in Figure 1, which is that of the first form, is differently shaped in elevation from the first form. As shown at 26, the lower surface is curved lengthwise in this form of the invention. This lengthwise curvature permits the insert to lay flat inside a shoe and conform to the lengthwise curvature thereof.

As previously stated, the preferred material from which the stabilizer pads are constructed is rubber of different densities but other materials may be used alone or in combination. The pads may be covered with leather, cloth or other suitable material and they may be made in various widths and lengths for different sizes of feet. While the construction which has been described herein constitutes a preferred embodiment of the invention it will be obvious that various changes and modifications may be made without departing from the principles of the invention as herein stated and as embodied in the ensuing claim.

Having described my invention, I claim:

A foot balancing pad for insertion in a shoe comprising a unitary sheet of resilient material having portions thereof of different densities; said pad conforming in outline substantially to the heel, arch and forward parts of the foot and including an upstanding flange formed on the upper surface of the pad and extending around the periphery of the heel portion and

along the medial side toward the arch, said flange providing a cup for confining the heel, said flange along the medial side being of greater height so as to direct the weight toward the lateral side, the portion of the pad directly forward of the heel cup on the medial side also being elevated to assist in the direction of the weight toward the lateral side, the portion of the pad directly beneath the medial arch being substantially soft and flexible, the portion on the lateral side beneath the cuboid bone being substantially hard and firm for sustaining the weight as it is transferred from the heel to the forward part of the foot in walking.
